UNITED STATES PATENT OFFICE

140,854

DESIGN FOR A ROSARY BEAD OR THE LIKE

Cornelius McNamara, Flushing, N. Y.

Application October 14, 1944, Serial No. 115,776

Term of patent 14 years

(Cl. D45—1)

To all whom it may concern:

Be it known that I, Cornelius McNamara, a citizen of the United States, residing at Flushing, in the county of Queens and State of New York, have invented a new, original, and ornamental Design for a Rosary Bead or the like, of which the following is a specification, reference being had to the accompanying drawing, forming part thereof.

Fig. 1 is a front view of a rosary bead or the like, showing my new design; and

Fig. 2 is a side view of the same.

This is a continuation-in-part of my application for patent, Serial No. D113,401, filed April 28, 1944.

I claim:

The ornamental design for a rosary bead or the like, substantially as shown.

CORNELIUS McNAMARA.
